United States Patent Office.

ROBERT W. PARK, OF PHILADELPHIA, PENNSYLVANIA.

Letters Patent No. 106,199, dated August 9, 1870.

IMPROVEMENT IN VAPOR-BURNERS.

The Schedule referred to in these Letters Patent and making part of the same.

To all whom it may concern:

Be it known that I, ROBERT W. PARK, of the city and county of Philadelphia, and State of Pennsylvania, have invented a new and improved Vapor-Burner; and I do hereby declare that the following is a full, clear, and exact description of the same, reference being had to the accompanying drawing, and to the letters of reference marked thereon, making part of this specification, in which—

Figure 1 is an external view, and

Figure 2 is a longitudinal section.

Similar letters refer to similar parts in the several views.

A is a wick-tube, which is connected to a lamp, or any other suitable fluid receptacle, by the screw B, at its lower end.

Its upper end is connected with the fluid or oil-chamber C by taking into its depending sleeve D, in such manner that the fluid from the lamp has free access to the said chamber, and also that its flow or quantity can be regulated by the distance the top of the said tube is adjusted or set from the circular bulb or outward projection a of the top of the fluid-chamber, or be entirely stopped by butting the top of the wick-tube against the said projection.

E is a truncated cone-shaped air-chamber on the wick-tube A, having its apex reversed, or downward. It is adjustable on the said tube, and perforated for the admission of air to the flame.

Its upper edge has the semicircular indentations F, for the more perfect circulation of air to the interior of the chamber.

To the upper edge of the said chamber is fixed the double truncated cone-shaped air-guide G. The intersection of the cones forms the junction between it and the air chamber.

The diameter of the upper edge is slightly larger than the diameter of the base b of the fluid-chamber C, leaving a circular space or opening, c, for the passage of air from the perforated cone to the flame. A

wick extends up the wick-tube A to within a convenient distance of its upper end.

On the fluid being admitted to the chamber C, it passes out the needle openings or gas-jets d, (in this case six are used, though I do not confine myself to any stated number,) and, on a match being applied to the fluid as it passes out, it becomes ignited and heats the metal of the chamber and converts the fluid into gas, which afterward becomes rarefied by the heat of the chamber and issues from the openings with considerable pressure.

The outwardly-projecting lower part of the double cone-shaped deflector G converges the air to the air-chamber E, thereby increasing the supply. The outwardly-projecting upper part of the same conveys the air out through the circular opening c, where it impinges on the flame, thereby adding greatly to its brilliancy, by producing a complete and thorough combustion of the gas as it issues from the needle orifices. Either one or both of the cones composing the deflector can be corrugated, if desirable.

The flame from the gas-jets also impinges on the upper edge of the deflector G, which adds to the vaporizing facilities of the burner.

What I claim as my invention, and desire to secure by Letters Patent, is—

1. The wick-tube A, fluid or vapor-chamber C, perforated air-chamber E, and the deflector G, when combined and arranged as shown and described.

2. The circular space c, between the edges of the rim b of the fluid-chamber C, and the upper truncated cone of the deflector G.

In testimony whereof I hereunto sign my name to this specification in presence of two subscribing witnesses.

ROBERT W. PARK.
